ARCH AND WALL

Paul Wright, Birmingham, Ala.

Application September 12, 1939, Serial No. 294,568

12 Claims. (Cl. 110—1)

This invention relates to arches, baffles or walls, and structures which may or may not utilize a cooling medium that passes through tubes related to same.

A general object of my invention is to provide for furnaces a structure that will endure high temperatures and transfer much of the heat passing through related tubes to a cooling medium; a structure that can be repaired or replaced in parts, while in or out of service; a structure that can provide surfaces disposed in horizontal, inclined, vertical and approximately curved sections. Such structures may have the form of an arch or baffle or wall.

A further object is to provide an enclosure for a refrigerated chamber, whereby heat within or without the chamber can be transferred to a cooling medium in related tubes so as to maintain a cold chamber enclosure.

A further specific object is to provide an arch or wall whose exposed surfaces will withstand fire on both sides; an arch that can be repaired or replaced in parts; an arch that can be flat, also be approximately shaped to a contour.

A further object is to provide an arch having a single tube or row of single tubes conveying a fluid cooling medium through same; an arch having a double tube or plurality of tubes spaced for conveying a fluid cooling medium through same.

A still further object is to provide tubes incased in a baffle which can withstand heat on both exposed sides of said baffle, whose parts can be repaired or replaced as specified and spaced passages provided through the baffle if desired.

A further object is to provide a fluid cooled baffle or arch constructed with tubes incased in parts having different degrees of heat absorption.

Another feature is to provide through the arch or wall structure, open passages or holes between the tubes, whereby the tubes are not exposed at said holes.

A further specific object is to provide an arch, baffle or lateral structure comprising a side of the type described, which has a wrapping or covering on the tubes for cushioning the impact between parts and related tubes so as to reduce breakage; and a further object is to provide for the wrapping or covering of said tubes with a means for retarding or increasing the flow of heat to the cooling medium within said tubes; and still further, an object of the said wrapping or covering of the tubes, is to effect an improved ad-

herence between the tubes and related structure.

The various features which characterize my invention are stipulated in the claims annexed to and forming a part of this specification. For an understanding of the invention, and specific objects attained by its use, reference should be had to the accompanying drawings and descriptive matter in which I have illustrated and described preferred embodiments of the invention.

10 Of the drawings:

Fig. 1 is a perspective view of a portion of an inclined arch embodying the invention. Such an arch may be used as a wall structure.

15 Fig. 2 is an end view of two similar tube blocks that comprise parts of the arch Fig. 1.

Fig. 3 is a side view of the tube blocks shown by Fig. 2.

20 Fig. 4 is an end view of an intermediate spacer that comprises a part of the arch Fig. 1.

Fig. 5 is a side view of the spacer shown by Fig. 4.

25 Fig. 6 is a side view of a modified tube block, which is formed to fit a curved tube.

Fig. 7 is a sectional view of Fig. 6, as taken on a radial plane.

30 Fig. 8 is an end view of the spacer shown in side view by Fig. 9. The forms illustrated by Figs. 6 and 9, are suitable for use together.

Fig. 10 is an end view of a side spacer block and Fig. 11 is a side view of the same.

35 Fig. 12 is a perspective view of a portion of a baffle embodying the invention and shows the tubes in upright position. The same construction may be arranged with the tubes horizontally disposed above each other.

40 Fig. 13 is an end view of two similar tube blocks that comprise part of the baffle Fig. 12, and Fig. 14 is a side view of the same, while Fig. 15 shows a sectional view, taken transversely of both blocks, on center of the tube.

45 Fig. 16 is an elevation of an assembly of a portion of a vertical baffle or wall embodying my invention and Fig. 17 is a sectional view of the assembly Fig. 16.

Fig. 18 is an assembly of tube blocks and intermediate spacers, showing said blocks with a modification of the recessed part.

50 Fig. 19 is an end view of two similar tube blocks arranged for two tubes and Fig. 20 is a side view of the same.

Fig. 21 shows an assembly of modified forms of tube blocks and a spacer as related to square tubes.

Fig. 22 shows a wrapped tube in contact with a tube block, of which Fig. 23 is an end view indicating the method of assembly as embodied in my invention.

Fig. 24 shows a further modified shape of tube blocks and spacer.

Fig. 25 shows a structure made with plane and curved portions, the view being in the plane of the curved tube. The blocks of Figs. 3 and 6 also the related spacers of Figs. 5 and 9, are used as shown.

In the arch embodying my invention as shown by Fig. 1, its position for this example, may with horizontal tubes, be inclined or horizontal. Tubes 1 preferably having a cooling medium passing through same, serve as tubular beams to support blocks 2 and spacers 3, placed as shown by Fig. 1. Also with tubes set upright or sloping, the construction may serve as a wall; furthermore, with tubes arranged one above another, the construction may serve as a wall.

The tube blocks 2 in this example, are shaped in a manner to contact the exterior surface of the tube, yet not touch each other when fitted around the tube and with adjacent sides approximately parallel. The spacers 3 are positioned between the tube blocks 2 with the lug end upward to prevent sliding downward.

Heretofore blocks incasing tubes have been used in boiler furnace walls; however such constructions have not employed intermediate spacers whereby individual blocks may be removed and replaced in the improved manner herein described.

Referring to Figs. 2-4, my novel arrangement for placing or removing blocks 2 and spacer 3 between tubes 1, is based on the relation that, the thickness of the intermediate spacer as at S+ shall be greater than the normal recessed depth of the adjacent tube block as at S. Thus in the assembly between two tubes, if spacer 3 be withdrawn, then a single tube block 2 adjacent may be withdrawn thereafter, permitting either or both blocks 2 on each side of the spacer to be removed and replaced, and from above or below the tubes.

As regards the shape of tube blocks as shown by Fig. 2, I have found by experiment that the side contacting the spacer may in the case of fire clay refractories, be made slightly tapered as shown, to avoid a tendency to bend the tube blocks under a possible wedging effect. This wedging occurs when placing blocks originally or when removing the blocks that may have their faces slagged after furnace service. This shape has a further advantage, that expansion between the assembled blocks and spacers is resisted between tube bearing surfaces and not near the exposed faces of the blocks. Thus if tubes be flexibly held in position, the arch can expand and contract without rupturing (for example) the cheaper fragile classes of material otherwise satisfactory for use.

A further specific advantage and novelty of my invention, is the facility and usefulness of being able to remove the individual blocks as shown by Fig. 2, which may have been fused or worn on the exposed side, and again placing same with the opposite face to the exposed positions. Thus the life of the blocks is lengthened in service, also the need for spare or replacement blocks is lessened.

The lug projection on intermediate spacers, also acts to prevent dust from entering between

the spacer lug portion and the adjoining block, providing the effect of a closed joint therebetween yet permitting a suitable clearance at the portions of spacer between the related blocks.

5 In Fig. 3, I show a companion view of Fig. 2, being blocks for straight tubes, Fig. 6 and Fig. 7 show a partial sector shaped to fit a curved portion of tube. With tube blocks like Figs. 6-7, I use spacers like Figs. 8-9.

10 An embodiment of my invention is illustrated by Fig. 12 in the form of an upright lateral structure that employs similar parts to those shown in Fig. 1 but these blocks are modified as shown by Figs. 13, 14, 15. Such a structure is 15 usable as a baffle or partition or wall, positioned in an upright or sloping position.

The type structure as of Fig. 12, provides an improvement over plastic refractory construction, as a baffle that incases upright tubes having 20 a furnace exposure, and with furnace gases passing against and beneath the baffle, as in a boiler.

An existing structure in the form of Fig. 12, 25 advantageously can be modified in size by taking off or adding the blocks and spacers so as to suit different furnace operating conditions related thereto.

Furthermore the structure shown by Fig. 12 is adaptable as a wall or partition where the tubes 30 are horizontally disposed above each other and, with the tubes in horizontal position, the lugs 4 are omitted. The lugs are not claimed as part of the invention.

Tubes 1a may have lugs 4 secured to same, 35 whereby blocks 2a would rest on lug 4, when necessary. An understanding of the features of these blocks 2a will be had from Fig. 13, Fig. 14 and Fig. 15 showing typical details. As Fig. 2 shows, provision is made for similar tube contact; but the spacer as in Fig. 4, Fig. 5 has its lug upper side transversed to the tube axis. Thus the tube blocks are shaped or grooved on the faces, to receive the lug of the spacer in a manner for it to slide in or out.

40 Therefore in similar manner to the assembly shown by Fig. 1, the tube blocks 2a and spacer 3 in Fig. 12 are removable. The arch of Fig. 1 can be constructed with the lug portion of the 50 spacer 3 made flush with the upper side of blocks 2, without departing from the invention.

Where it is desirable to provide passage 3b through the wall yet not expose the tube, a shortened spacer like 3a corresponding to Figs. 54 and 5 can be advantageously employed.

Fig. 10 and Fig. 11 show a spacer with lug on one side to contact the tube block and the other side flat to adjoin a wall surface.

In the modification illustrated by Figs. 16 and 60 17, I show the construction example of a boiler wall in vertical or sloping position, wherein the tube blocks have a greater degree of heat absorption than the spacers. For tubes spaced in customary wide and narrow rows as shown, the clearances for using parts like Fig. 2 and Fig. 4 may be limiting, where for example thinner sections may advantageously be made of metal instead of refractory for the blocks contacting the tubes, yet of refractory for the spacers. For ordinary boiler uses, I prefer cast iron for the tube blocks, whereby heat will be conducted to the tubes. The refractory serves as a filler between these metal shapes; it reflects heat and resists passage of heat through the intermediate spacers. Refractory spacers usually cost less and

weigh less than metal spacers, although metal could be used.

In Figs. 16 and 17, tubes 1b may be provided with welded supports 4b which extend partially into the narrow space between tubes, hence do not interfere with tube removal through the other wide spaces. Tubes 1c may be provided with narrow supports 4c that clear the space between tubes. The use of supports 4b and 4c is optional.

My novel arrangement of Fig. 17 for placing or removing the blocks contacting the tubes, also the spacers, is understood from the relation existing; that the spacer is wider (indicated by S+) than the depth of recess of the block contacting the tube (indicated by S).

In Fig. 16, the metal blocks 5 contacting tubes 1b and 1c are shaped to fit the tube and are used in the wide space and can rest on supports 4b and 4c as shown. Also blocks 5 have a lug at the bottom, to support the spacers 8 or 8a as shown. Blocks 6 are similar to 5 but do not have the lugs, as 8 extends the height of 5 plus 6, or less as for 8a. Likewise metal blocks 7 contacting tubes, are used in the narrow space and can rest on supports 4b and 4c as shown, also spacers 9 are placed as shown. By using a spacer 8a of length less than 5 and 6 combined, an opening 8b through the structure is provided, yet the tube is not exposed.

Obviously the structural parts can be placed or removed from either side if adjacent clearance permits; the structure is suitable and satisfactory for exposure of either or both sides as a conductive tube covering. The construction is not limited to boilers.

I do not limit my invention to the exact shapes of recessed blocks and spacers as shown by the drawings, since the lug of the spacer and the corresponding groove of the block related, are changeable in shape without departing from the specification and the claims. Also the invention is not limited to blocks that are symmetrical in pairs, since related blocks may be made one thicker than the other, as shown in Fig. 17. Also Fig. 16 shows spacers 8 that are wider than blocks 5 or 6.

Fig. 18 shows an embodiment of my invention, utilizing a relatively stronger material than fire clay refractory for the tube blocks and a material which will reasonably resist compression due to expansion. The related spacer is made of material that will allow for a compression, such as expansion would produce. As one example of this assembly, I prefer silicon carbide to make the tube blocks and refractory plastic combined with mineral wool, to make up the spacer. As in Fig. 18 the tube blocks can abut about the tube, as the hole through same is suitably larger than the tube on which said blocks are supported. The upper part of the spacer forms an effective seal, altho the flat part of the spacer may have been slightly compressed.

Another form of tube block is shown by Fig. 19 and Fig. 20, as arranged for use with either two single tubes or two tubes having an integral web between them. For wide spans of arch, the combination of two tubes furnishes a stiffer and stronger beam than a single tube, where the same size tubes are employed; further, a tubular beam supporting two tubes integrally joined with a web, furnishes a still stiffer and stronger beam than the two tubes not so joined.

An advantage of two or more tubes thus em-

ployed is the facility to provide increased area for the fluid therein to absorb heat, resulting in safer supports under high temperature service.

Fig. 21 is an illustration of the use of square tubes instead of round tubes, in other illustrations I've shown, for the invention is not limited to the shape of the tube acting as a support and conveyor of a cooling medium.

In practice I have discovered there are advantages and improvements gained by wrapping or covering the tube with a softer material (than the tubes are made of) for the purpose of cushioning the impact between blocks and tubes. For example, I illustrate in Fig. 22 and Fig. 23 a wrapping 10 of strip asbestos composition around the tube 1. The asbestos composition will accommodate the ordinary unevenness of refractory blocks to a fit about the tube, without having to unduly crush uneven projections or surfaces not true to intended shape. The wrapping is advantageous to offset the effects of deformation due to deflection of the tubular beam under loadings causing deflection. A further improvement by wrapping or covering with an insulating type of strip is the retarding of heat flow to the tube and its cooling medium, and thus the rate of absorption can be varied by the proportion of insulation employed. This is useful in providing an arch intended to "soak heat" for intensifying reflected heat conditions about same.

Another example of my invention of the wrapping feature is illustrated by applying strip or sheet lead about the tubes. The lead being softer than the blocks will provide an improved contact between the tube and block as pressed together. Also the lead being a better conductor of heat than refractory, it serves to improve heat transfer between block and tube. A soft metal wrapping or covering, as for example of strip lead, is also advantageous to cover the tubes for assembling metal tube blocks, as in the forms shown by Figs. 16 and 17.

For example, such cast iron blocks usually are machined to assure tube contact; but my improvement of using a soft metal tube covering permits using cast blocks thereon not machined, and thereby the cost is less than for machined blocks. Furthermore, my use of the tube wrapping or covering, in combination with silicon carbide blocks is advantageous in improving the adherence and fit of said blocks to the tubes.

Furnace roof closures have heretofore been used, that employ tapered blocks supported from structural supports and having tapered wedge blocks intermediate with the supported blocks. Also a conditional use of such construction is usually that one side must be exposed to atmosphere for cooling the support. By comparison my invention as illustrated by Fig. 24, provides tapered tube blocks with an intermediate tapered wedge, which structure protects the tube and assures its functioning as a beam and conveyor of the cooling medium, with exposure to extreme heat or cold on either or both sides.

In some arches and walls of this invention, I use the tubes without circulating a cooling medium through same. In others where a cooling medium is used, I prefer to employ air, gas, oil, steam or water, in various structures and I therefore use the term "cooling medium" as a general description for any of these. But I do not limit the kind of cooling medium to those named, since there are other heat absorbing

substances that are usable as a cooling medium, also suitable to my invention.

What is claimed is:

1. An imperforate structure subjected to the action of heat,—said structure a plurality of substantially parallel tubes, a plurality of spaced rows of blocks each of said rows including pairs of contacting blocks provided with recesses and surrounding one of said tubes; and spacers between the blocks in one of said rows and the blocks in an adjacent row, to hold said blocks in place on said tubes; each spacer comprised of one piece whose width is that of the adjacent blocks and whose thickness exceeds the depth of the tube recess in the adjacent blocks,—whereby each block is directly removable transversely to either side of said structure, after the contacting spacer is removed.

2. The structure of claim 1 in which said blocks and spacers are so shaped and arranged that they are reversible after being worn by usage.

3. The structure of claim 1, in which the lateral surface of said structure has plane and curved portions.

4. In a furnace, a structure that comprises a plurality of substantially parallel tubes, a layer of insulation in contact with and surrounding said tubes; a plurality of spaced rows of blocks each of said rows including pairs of contacting blocks provided with recesses and surrounding one of said insulated tubes; and spacers occupying the space between the blocks in one of said rows and the blocks in an adjacent row, to hold said blocks in place on said insulated tubes; each spacer comprised of one piece whose thickness exceeds the depth of the tube recess in the adjacent blocks,—whereby said structure retards the passage of heat to said tubes thus permitting said blocks and spacers to absorb heat.

5. A structure subjected to the action of heat,—said structure a plurality of substantially parallel tubes, a layer of cushioning material around and in contact with said tubes; a plurality of spaced rows of blocks, each of said rows including pairs of contacting blocks provided with recesses and surrounding one of said cushioned tubes; and spacers occupying the space between the blocks in one of said rows and the blocks in an adjacent row, to hold said blocks in place on said cushioned tubes; each spacer comprised of one piece whose thickness exceeds the depth of the tube recess in the adjacent blocks,—whereby said cushioning material will decrease breakage due to the expansive action of heat within said structure.

6. A wall comprising a plurality of substantially parallel tubes, a plurality of spaced rows of blocks each of said rows including pairs of contacting blocks provided with recesses and surrounding one of said tubes; and lug shaped spacers occupying the space between the blocks in one of said rows and the blocks in an adjacent row, to hold said blocks in assembled relation on said tubes; each spacer comprised of one piece whose portions of different thicknesses form its said lug shape whereby the minimum thickness of said spacer exceeds the depth of the tube recess in the adjacent blocks.

7. A structure that comprises a plurality of substantially parallel tubes, a plurality of spaced rows of blocks each of said rows including pairs

of contacting blocks provided with recesses and surrounding one of said tubes; and spacers occupying the space between the blocks in one of said rows and the blocks in an adjacent row thereby holding said blocks in place on said tubes; each spacer composed of material less firm and more resilient than the material of said block, and each spacer comprised of one piece whose thickness exceeds the depth of the tube recess in the adjacent blocks, whereby the pressure between said blocks is decreased during the expansion of said structure.

8. In a structure of the character described, a row of spaced substantially parallel tubes, co-operating pairs of tube blocks incasing said tubes,—each block having a recess therein partially embracing its associated tube, and spacers occupying the space between the blocks on adjacent tubes thereby holding said blocks in place whereby the side of the block contacting the spacer is opposite the block's side that is recessed, and each spacer having a thickness greater than the depth of the recesses in the adjacent blocks.

9. In a structure of the character described, a row of spaced substantially parallel tubes, co-operating pairs of tube blocks incasing said tubes,—each block having a recess therein partially embracing its associated tube, and spacers occupying the space between the blocks on adjacent tubes to hold said blocks in place whereby the side of the block contacting the spacer is opposite the block's side that is recessed, and each spacer having a thickness greater than the depth of the recesses in the adjacent blocks, and said spacers arranged to provide thru said structure holes which are bounded by said separated spacers and related blocks.

10. In a structure of the character described, a row of spaced substantially parallel tubes, co-operating pairs of tube blocks incasing said tubes,—each block having a recess therein partially embracing its associated tube, and spacers occupying the space between the blocks on adjacent tubes thereby holding said blocks in place whereby the side of the block contacting the spacer is opposite the block's side that is recessed, and each spacer having a thickness greater than the depth of the recesses in the adjacent blocks, and a cushioning material interposed between the blocks and the tubes.

11. In a structure of the character described, a pair of substantially parallel tubes and between said tubes two rows of co-operating blocks each having a recess therein partially embracing one of said tubes, and unitary spacers occupying the space between said blocks in one of said rows and the blocks of the adjacent row, and each spacer of a thickness that exceeds the depth of recess in the adjacent blocks.

12. In a structure of the character described, a pair of substantially parallel tubes and between said tubes two rows of co-operating blocks each having a recess therein partially embracing one of said tubes, and unitary spacers arranged in the space between said blocks in one of said rows and the blocks of the adjacent row to hold said blocks in place, and each spacer of a thickness that exceeds the depth of recess in the adjacent blocks, and said unitary spacers disposed to provide openings thru said structure.

PAUL WRIGHT.
